UNITED STATES PATENT OFFICE.

WILLIAM G. FLINT, OF COLTON, CALIFORNIA.

DESIGN FOR A HANDLE CUP.

Application filed March 7, 1925. Serial No. 12,641. Term of patent 14 years.

To all whom it may concern:

Be it known that I, WILLIAM G. FLINT, a citizen of the United States, residing at Colton, in the county of San Bernardino and State of California, have invented a new, original, and ornamental Design for a Handle Cup, of which the following is a specification, reference being had to the accompanying drawing, forming part thereof,

The figure is a perspective view of a handle cup, showing my new design.

I claim:

The ornamental design for a handle cup, as shown.

WILLIAM G. FLINT,
